UNITED STATES PATENT OFFICE

FREDERIC SHIPMAN, OF SAN FRANCISCO, CALIFORNIA

REFLECTOR

Application filed March 27, 1929. Serial No. 350,222.

My invention relates to reflectors and is particularly adapted to reflectors for illuminating indicia.

It is an object of my invention to provide a novel reflector construction of simple design for producing a uniform, intense illumination.

An object of my invention is to provide a novel reflector construction which may be used to illuminate signs of different dimensions.

Another object of my invention is to illuminate an indicia with a plurality of images of a true line source of light.

15 A further object of my invention is to reduce to a minimum the number of light sources required to secure a concentrated illumination.

The invention possesses other advantageous features, some of which with the foregoing will be set forth at length in the following description where I shall outline in full that form of the reflector of my invention, which I have selected for illustration in the drawings accompanying and forming part of the present specification. In said drawings I have shown one form of the reflector embodying my invention, but it is to be understood that I do not limit myself to such form since 30 the invention, as set forth in the claims, may be embodied in a plurality of forms.

In the drawings to which I have made reference, Fig. 1 is a perspective view of a reflector of my invention.

35 Fig. 2 is a side elevation of a form of the reflector of my invention.

Fig. 3 is a fragmentary plan view of a form of the reflector of my invention.

40 Fig. 4 is a front elevation of the reflector of my invention shown in Figure 2.

Fig. 5 is a diagrammatic illustration of the manner of reflection attained in a form of reflector of my invention.

45 Fig. 6 is a side elevation of a sign embodying a reflector of my invention.

Fig. 7 is a front elevation partly in section of a sign embodying a form of the reflector of my invention.

50 Fig. 8 is a cross section on the line 8—8 of the device shown in Fig. 7.

Fig. 9 is a cross section on a vertical transverse plane through a sign employing a reflector of my invention.

Fig. 10 is a plan view of the sign shown in Fig. 9, partly cut away to show details thereof.

Fig. 11 is a front elevation of the sign shown in Figures 9 and 10, partly cut away to show details thereof.

In its preferred form the device of my invention comprises a reflector adapted to illuminate an indicium by means of repeated and closely related images of a source of light. It is particularly useful in illuminating window and other signs and it is in that connection that I shall describe it.

As I have shown in the drawings, the device of my invention preferably comprises a reflector, indicated generally as 6, constructed of a light reflecting material such as 70 nickelized zinc or other suitable material having a bright reflecting surface. The reflector is usually formed of a reflecting sheet 7 and a second reflecting sheet 8 angularly positioned with respect to sheet 7. The sheets converge 75 in the same direction toward a common line of convergence. To facilitate the manufacture of the device, I preferably provide a third reflecting sheet 9 adjacent to the common line of convergence of the reflecting 80 sheets. The reflecting surfaces, as is shown particularly in Fig. 2, are relatively close together where they are joined to the third reflecting sheet 9. The several sheets are preferably joined together by hinge sections 10 85 for reasons which will hereinafter appear.

I prefer to use a line source of illumination, in combination with the reflector of my invention, where a bright, uniform and intense lighting effect is desired and, to secure such 90 illumination, neon tubes of a suitable size or ordinary tungsten filament lamps are used. Thus in Figures 7, 8 and 9 I have shown, cooperatively positioned with respect to reflector 6, lamp 16 secured in socket 17 and attached to a source of current by wires 18.

To secure the most uniform, intense illumination and to reduce the area in which flood illumination occurs I preferably position only that portion of the light source between 95 100

the reflector which is active in emanating light. Thus, as is shown particularly in Fig. 9, lamps 16 are positioned adjacent to the line of convergence of the reflecting surfaces 7 and 8. A filament structure 22 provided within the lamp serves to produce an illumination. The lamp is preferably positioned through apertures, indicated by 23, in the reflecting surfaces so that substantially only that portion of the lamp containing the luminous filament is within the confines of the reflecting surfaces. Images of only the light source, in this instance the luminous filament, are reflected between the surfaces, as illustrated in Figure 5. This produces an intense, uniform illumination and reduces the number of lights required to a minimum.

A source of light is preferably positioned adjacent to the intersection of the plane reflecting sheets and relatively close to the reflecting sheets. By thus placing the light source, a greater number of light source images are visible when the reflector is viewed and the area in which only flood illumination of the reflectors occurs is decreased to a minimum. If the source of light is placed at a considerable distance from the reflectors the images of the light source, which are formed, are spaced at relatively greater distances from each other. The hiatus between the images is also greatly increased and is of such a nature that dark bands appear between them. The increase in the hiatus thus interrupts the desired continuity of light source images with the result that the uniformity of light from the reflector is undesirably destroyed. The positioning of the light source adjacent to the intersection of the sheets obviates these objections.

To illuminate an indicium with the same relative degree of illumination, irrespective of the position of the observer, I preferably construct the device of my invention so that images of the light source are always available to illuminate the indicia no matter whether the observer be directly in front of the indicium or standing over it and viewing the indicium in almost the same plane. To accomplish this I preferably provide plane reflecting surfaces 27 and 28 which respectively form continuations substantially of surfaces 7 and 8. These surfaces are preferably angularly positioned with respect to surfaces 7 and 8 so as to secure the desired repetition of images therein.

When a person is viewing from a distance an indicium, illuminated by the reflector of my invention, the indicium is illuminated by images of the light source reflected from surfaces 7 and 8. However, if the person takes a position almost directly over the indicium, the light source images are reflected from the surfaces 27 and 28, which continue surfaces 7 and 8. Without the provision of the continuing surfaces the illumination of the in-

dicium when viewed from above, would be only by the flood illumination from the light source and not by the intense, uniform light from the light source images.

The reflecting sheets are preferably manufactured with end reflecting sheets 31 which serve to reflect images of the light source and to intensify the illumination secured from the reflector. The end sheets are expediently joined to the reflecting sheets by any convenient method such as by soldering.

In some instances I have found it desirable to have a single reflector for illuminating indicia of various sizes. The device of my invention is preferably constructed to facilitate the altering of the reflector to secure a concentrated illumination upon the particular indicia used. Thus, as is shown particularly in Fig. 2, end sheets 31 are joined preferably to only one of the reflecting sheets and the angularity of the reflecting sheets is varied by any convenient means as turnbuckles 32 attached to the reflecting sheets by ears 33, the reflecting surfaces 7 and 8 turning upon the hinges 10 provided at their juncture with sheet 9. As is shown particularly in Fig. 2 the surfaces 27 and 28 are also preferably adjustable with respect to each other and to surfaces 7 and 8. Turnbuckles 39 positioned between ears 40, which are attached to surfaces 27 and 28, serve to adjust the angularity of these surfaces and, in combination with turnbuckles 32, to accommodate the reflecting surfaces to indicia of different sizes. The adjustment of the reflector is readily accomplished, and, when it is desired to position an indicium before the reflector of a size different from that previously positioned, the reflector is readily accommodated to illuminate intensely the indicium with images of the light source and with a minimum quantity of flood illumination.

One manner in which the device of my invention is utilized is in a window sign such as is shown in Figures 6 to 11 inclusive. A sheet metal casing 41 of a convenient size and shape is constructed with an opening, indicated by 42, in one side of the casing. An indicium 43, such as one of the usual stencilled indicia, is preferably positioned over the opening 42 by a frame 44 which is conveniently retained upon the casing by tongue 46 overlapping upturned edge 47 of the casing.

Positioned adjacent to the indicium 43 is a diffusing plate 48 such as prismatic, ruffled or rippled glass or any glass for deflecting direct light rays. The surface of the plate is preferably of such a nature that concentrated or distorted image points appear when it is viewed through the indicium. Other diffusing plates may be used or other means employed as I have disclosed in my several co-pending applications, particularly application, Serial No. 311,271, filed October 9, 1928.

The diffusing plate 48 is preferably posi-

tioned adjacent to the indicia by means of a groove 49 formed in the surface of the reflector 6. This groove retains the plate and, together with opposite edge 52 of the reflector, positions the plate between the reflector and the indicia 43. Preferably disposed between the source of light, and the plate 48 is a color filter 53 composed of any desired combination of colors. The color filter is expediently positioned as by means of grooves 56 formed in the surfaces of the reflector 6.

In operation it is characteristic of my invention that the indicia are clearly and vividly outlined, even against bright day light. The various letters of the indicia, depending upon the combination of colors composing the filter interposed between the light source and the indicia, appear as various colors and combinations of colors. Furthermore, and what is even more characteristic, an indicium when viewed with only the diffusing plate interposed between it and the light source, is a brilliant silver, standing out clearly and distinctly.

To an observer moving relative to an indicium, illuminated by a reflector of my invention, the indicium assumes many different color outlines and combinations of colors. The vividness and brilliancy of the letters and the distinctness with which they are set off, even against bright day light, is of the highest degree.

I claim:

1. A light reflecting device for illuminating a sign plate comprising a plurality of reflecting surfaces extending from a common line, a plurality of reflecting surfaces connected to said first reflecting surfaces, a line source of light disposed substantially adjacent to the convergence of said first surfaces, means for adjusting the angularity of the first reflecting surfaces and means for adjusting the second plurality of reflecting surfaces in relation to the first reflecting surfaces independently of the adjustment of the first surfaces.

2. A light reflecting device for illuminating a sign plate comprising a plurality of plane reflecting surfaces angularly positioned with respect to each other, a line source of light adjacent to the point of convergence of said reflecting surfaces, a plurality of reflecting surfaces extending from said first reflecting surfaces, hinges connecting the first and second plurality of reflecting surfaces and means for adjusting the angularity of the first and second reflecting surfaces independently of each other.

In testimony whereof, I have hereunto set my hand.

FREDERIC SHIPMAN.
